T-SQUARE

Harold L. De Lisle, Sheboygan, Wis.

Application June 26, 1939, Serial No. 281,116

8 Claims.

(Cl. 33—99)

This invention relates to T-squares more particularly for use by mechanical draftsmen or the like, and aims to provide an improved device of this class.

Among other objects, the invention contemplates the provision of a movable head, and in one aspect, a pair of such heads. By this arrangement space is saved in shipping or stocking the T-squares and, furthermore, one of the heads may be arranged to swivel so as to afford relative angular adjustments of the head and blade.

In accordance with the present invention the blade of the improved T-square may be separable from at least one of the heads, for example, the swivel head, so that the device may be used with or without the latter. Furthermore, common means are advantageously contemplated for securing or pivoting the heads to the blade, thus effecting economy and simplicity.

The invention also desirably includes means for rectifying the straight edge of the head if variations occur from constant use.

Other objects and advantages will be apparent from the following description taken together with the accompanying drawing, in which—

Figure 1 is a partial plan view of the blade and one of the heads, an alternative selective position of this head being shown in broken lines;

Figure 2 is an enlarged partial longitudinal section taken on the line 2—2 of Fig. 1;

Figure 3 is an exploded fragmentary view of parts shown in Figs. 1 and 2, slightly less enlarged than Fig. 2;

Figure 4 is a perspective view of another head for the device with associated parts in separated relation, on the scale of Fig. 1;

Figure 5 is a still further enlarged cross-section taken on the line 5—5 of Fig. 1 but also showing the parts of Fig. 4 associated with the structure of Fig. 1; and

Figure 6 is an enlarged plan view of the lower part shown in perspective in Fig. 4.

In the illustrative construction shown in the drawing, 10 is in general the elongated blade (discontinued at its right-hand end to save space) of a draftsman's T-square, and 11 is a head therefor. This head 11 may occupy with respect to the blade 10 one of two alternative positions either at ninety degrees with respect to the blade as shown in full lines in Fig. 1 or at one hundred and eighty degrees, that is, parallel thereto, as shown in broken lines. The head and central longitudinal part 12a of the blade are desirably formed of a phenolic condensation product such as "Bakelite," and the straight edges 12 of the blade may be advantageously made of Celluloid or such transparent material dove-tailed into the main body of the blade as at 13 and of slightly less thickness than the blade, as is well known in the art.

In accordance with the present invention the blade at its left-hand end is perforated as at 14 and the head 11 is similarly perforated as at 15 to provide a bearing for an interiorly threaded sleeve 16 which is one of the parts for securing the head and blade together. Surrounding the perforation 14 in the blade is a metal plate 17 which is desirably square and which at its four corners is secured by pins 18 to the upper face 10 of the blade, the pins 18 extending through the blade to project slightly from its under face as at 19. These pins are arranged to define a square, the center of which is a perforation 20 in the plate 17 registering with the perforation 14 in the blade and two sides of which are parallel to the straight edges 12 of the blade. The pins 18 desirably have a tight drive fit in the blade.

The head 11 has not only the perforation 15 registering with the perforations 14 and 20 but also has pin holes 21 adapted to register with the lower ends 19 of the pins 18.

Since the pin holes 21 are arranged in a square similar to the square defined by the pins 18 and two sides of which are parallel to the straight edge 22 of the head, when the pins 18 are received in the pin holes 21, acting as pilot holes, the head may be in either ninety-degrees relation or one hundred and eighty degrees relation to the blade, as already referred to and as shown in Fig. 1. In either position the parts are secured together in this instance by a screw 23, the shank of which passes through the under side of the head and into the threaded sleeve 16. Since this sleeve 16 has a flanged part 24 which laps the plate 17 on the upper face of the blade, the parts are thus clamped together as best shown in Fig. 2, a washer 25 being desirably inserted between the screw 23 and the lower face of the head to minimize wear thereon.

The device thus far described is a complete T-square and may be used as such, when the parts are in full line position shown in Fig. 1, after having been shipped or stored in dotted line position.

Since it has been found that constant use of the T-square tends to wear the ends of the head at the points 26 on the straight edge surface 22, the present invention contemplates means for correcting a deviation from the straight at these points. For this purpose the head 11 is shown split from its rear edge 27 inwardly to the perforation 15 as at 28 and within this split means are provided for spreading the head in the vicinity of the split, such means being here represented by the set-screw 29 which is screwed into a pair of opposed semi-cylindrical cuts forming jointly a bore 30 in the head concentric with the split 28. By tightening this set-screw 29, that is, by screwing it further into the head, the surfaces 26 are forced in a direction away from the rear surface

27 of the head and into line with the straight edge 22 to compensate for wear thereon.

When, now, it is desired to include a swivel head in the combination, the head 31 may be used which may be substantially the same in size and shape as the head 11, and have the perforation 32 centrally therein to register with the perforations 14, 15 and 20 already described.

In accordance with the present invention, the sleeve 16 provides common means for securing both the head 11 and the head 31 to the blade, and for this purpose a knurled thumb stud 33 has a threaded shank 34 which is received in the interiorly threaded sleeve 16 similarly to the screw 23 but from the opposite or upper end, the shank 34 passing rotatably through the perforation 32.

In order to reduce the space occupied by the parts, the under face of the head 31 has a cylindrical recess 35 which rotatably receives the flanged part 24 of the sleeve 16. Also margining the recess 35 is desirably another cylindrical recess or counterbore 36 in the face of the head 31 which houses a friction-producing member as here shown in the form of a pronged ring 37, the prongs 38 of which are tilted as best shown at 39, so as both to grip the wall of the recess 36, into which they may be pressed, and also to scrapingly engage the plate 17 about its perforation 20 when the knurled stud 33 is tightened to clamp the parts together, as best shown in Fig. 5. A washer 40 may be inserted between the stud and the upper face of the head 31 to minimize wear at this point.

Thus the head 31 may be adjusted by means of releasing and then clamping the thumb-stud 33 at any relative selective angular position infinitely with respect to the blade 10 while the head 11 may be fixed at the right-angular position as shown in full lines in Fig. 1. As is well known in the art, the T-square may be reversed either to use one of the heads such as the head 11 as a right-angle T-square, or to use the head 31 for drawing parallel lines at an angle, for example. In either case the straight edge 22 of the head 11 or the straight edge 43 of the head 31, depending upon which head is being used, will engage the edge of the drawing board.

The under face of the blade may have a longitudinal groove 41 therein to minimize friction upon the table top when the T-square is used and also to minimize warping of the blade, and the straight edge 22 of the head 11 may have a depression 42 therein aligned with the slit 28 to facilitate action of the head under the influence of the set-screw 29 as already described.

So constructed and arranged, with a minimum number of parts the T-square may be used with or without the swivel head. In fact, it is feasible to sell the T-square in large quantities without the swivel head and its associated parts shown in Fig. 4, and later the purchaser of the T-square may obtain the swivel head parts to incorporate with the device with economy of both parts and cost.

Having described my invention, I claim—

1. As an article of manufacture, a T-square embodying a blade and a head movable with respect to the blade wherein the blade and head are perforated for the reception of a pivot member and the head is of somewhat resilient material and is split from its rear edge to its said perforation and wherein the head carries means for spreading the said split against the resilience of the head material.

2. As an article of manufacture, a head for a T-square embodying a straight edge surface and a rear surface, said head being perforated medially of its length and medially of said surface and being split from said rear surface to said perforation, and a set-screw in said split whereby screwing in of the said screw will spread the head in the vicinity of said split to force the ends of the head in a direction away from said rear surface.

3. In a T-square embodying a blade and head, having registering pivotal perforations, a plate margining the perforation in said blade, a threaded sleeve having a shank part passing through said perforations in the plate and blade, and having a flanged part lapping said plate, a circular recess in the head margining the perforation in the head and rotatably receiving the flanged part of said sleeve, and a knurled stud passing through the perforation in the head and threadedly received in said sleeve.

4. The structure of claim 3 wherein there is a pronged friction-producing member also margining said perforation in the head and adapted to frictionally engage said plate when the stud is screwed into the sleeve.

5. The structure of claim 3 wherein the said plate is secured to the blade by pins which pass through the blade and project upon its opposite surface and are adapted to be received in pin holes in a second head.

6. The structure of claim 3 wherein the said plate is secured to the blade by pins which pass through the blade and project upon its opposite surface and are adapted to be received in pin holes in a second head, and wherein the said second head is also clamped to said blade by a screw threadedly received in said sleeve.

7. In a T-square, the combination of a blade having a pair of removable heads, common means for fixing the heads to the blade including a sleeve open at both ends and interiorly threaded substantially throughout its length, said sleeve having a flanged part at one end and a shank part, said flanged part being adapted to lap the blade, perforations in the blade and one of the heads receiving said shank part therethrough, a clamping screw threadedly received in the sleeve shank part from its end opposite its flanged part for clamping the head receiving the shank part therethrough to the blade, a perforation in the other head, and a second clamping screw passing therethrough and threadedly into the sleeve at its flanged end.

8. In a T-square, the combination of a blade having a removable head, means for fixing the head to the blade including a member threaded at both ends, said member having a flanged part at one end and a shank part, perforations in the blade and head receiving said shank part, the flanged part lapping the blade upon its side opposite to the head, and a clamping screw having threaded engagement with the shank part at the shank part end opposite the flanged part for clamping the head to the blade, said member being interiorly threaded at its flanged end and open at its flanged end to threadedly receive another clamping screw in its flanged end to clamp a second head to the blade, whereby the second head may swivel on the blade.

HAROLD L. DE LISLE.
